INERTIA RESPONSIVE TURNING SIGNAL FOR MOTOR VEHICLES OR SIMILAR ARTICLE

Eli Allen Weston, 3512 Shasta Ave.,
Boise, Idaho 83703

Filed Apr. 26, 1968, Ser. No. 11,632

Term of patent 14 years

Int. Cl. D29—99

U.S. Cl. D72—1

FIG. 1

FIG. 2

FIGURE 1 is a right front isometric view of the inertia responsive turning signal for vehicles or similar article embodying my new design in the rest position.

FIGURE 2 is a left rear isometric view thereof.

I claim:

The ornamental design for an inertia responsive turning signal for motor vehicles or similar article, substantially as shown.
